Primary Examiner—Louis S. Zarfas

(57) **CLAIM**

The ornamental design for a skin treatment article, as shown and described.

DESCRIPTION

FIG. 1 is a front elevational view of a skin treatment article showing our design.

FIG. 2 is a side elevational view thereof; and,

FIG. 3 is a rear elevational view thereof.

The portions illustrated in broken line are for illustrative purposes only and form no part of the claimed design.
